UNITED STATES PATENT OFFICE.

JOHANN F. THEODORE BERGER, OF MOUNT CLEMENS, MICHIGAN.

ROAD-SCRAPER.

1,037,194.

Specification of Letters Patent. Patented Sept. 3, 1912.

Application filed April 15, 1912. Serial No. 690,693.

To all whom it may concern:

Be it known that I, JOHANN F. T. BERGER, a citizen of the United States of America, residing at Mount Clemens, in the county of Macomb and State of Michigan, have invented certain new and useful Improvements in Road-Scrapers, of which the following is a specification, reference being had therein to the accompanying drawings.

10 This invention relates to improvements in road scrapers especially adapted for scraping and leveling the surface of the road and its object is to provide a construction which is such that the rough and uneven surface 15 of the road is cut away by a scraper and the dirt thus scraped and loosened from the surface is again distributed over the same surface and deposited in the depressions thus leaving a smooth even surface to the 20 road-bed in going over the road but once with a scraper embodying this invention.

To this end the invention consists in the matters hereinafter set forth and more particularly pointed out in the claims reference 25 being had to the accompanying drawing in which—

Figure 1 is a plan view of a device embodying the invention; Fig. 2 a longitudinal section thereof on the line $x-x$ of Fig. 1; 30 and Fig. 3 is a transverse section on the line $y-y$ of Fig. 1.

As shown in the drawing two runners 10, 10 are connected in spaced relation by transverse rods 11 and brace members 12 and 13. 35 These runners are each preferably formed of planking without openings from end to end thereof so that the dirt which is scraped from the surface of the road-bed by the scraper 14 will be prevented from escaping 40 laterally from between these vertical walls formed by the runners. The scraper 14 consists of a blade mounted in guides 15 upon the inner sides of the runners and extending diagonally across between the runners. 45 This blade may be of any desired construction and form and is adjusted vertically in its guides by any suitable means such as screw-threaded rods 16 having hand wheels 17 upon their upper ends and engaging nuts 18 supported upon a cross bar 19 extending from one runner to the other. The blade 14 is notched or cut away at 20 adjacent to one of the runners and at the rearmost end of the blade. The dirt which 55 is scraped and loosened from the surface of the road-bed by the blade is thus per-

mitted when it passes along the inclined or diagonal side of the blade to the rearmost end thereof, to pass through said opening 20 to the rear side of the blade. A leveling 60 bar 21 located rearwardly of the scraper blade, extends diagonally across between the runners in an opposite diagonal direction from that in which the blade extends. The lower edge of this bar is even with the lower 65 edges of the runners and thus the dirt which passes through the opening 20 in the blade comes into contact with the forward side of the leveling bar and is distributed by said bar, because of its inclination, across the 70 surface of the road between the runners and fills the depressions in the road surface. As the bar 21 extends across between the runners with its lower edge in the plane of the 75 lower edges of the runners, there is no chance for the loose dirt to escape from between the runners except by dropping into the depressions in the road surface and passing beneath the leveling bar.

In this construction all of the dirt which 80 is scraped from the surface by the scraper blade is held by the runners from escaping laterally and is then distributed over the surfaces between the runners to fill in the depression in the road surface by the leveling bar. There is therefore no ridge of dirt 85 left at one side of the path of the scraper as is usually the case with road scrapers and therefore the surface passed over by this road scraping and leveling machine will be 90 leveled by one passage of the machine over the surface while with a machine of the usual type it is required to be passed over the surface several times in order to level off the ridge of dirt which is left at one side of 95 the scraper.

Obviously, changes in the construction and arrangement of parts may be made without departing from the spirit of my invention and I therefore do not wish to 100 limit myself to the particular form and construction shown.

Having thus fully described my invention what I claim is—

1. In a device of the character described, 105 the combination of runners spaced apart and forming side walls to prevent the escape of material laterally from between said runners, a scraper blade extending diagonally across between said runners and provided with an opening near its rearmost end adjacent to one of the runners to permit ma- 110

- terial to pass therethrough and a leveling member extending across between said runners rearwardly of said blade and in a diagonal direction opposite to that of the blade.
- 5 2. In a device of the character described, the combination of runners spaced apart and forming side walls to prevent the lateral escape of material from between said runners, a scraper blade extending diagonally across between said runners and having a portion cut away from its lower edge adjacent to its rearmost end forming an opening adjacent to one of the runners for the passage of material therethrough,
- 10 15 means for adjusting the blade vertically, and a leveling member extending between said runners in a diagonal direction opposite to that of the blade with its lower edge in the plane of the lower edges of the runners, said leveling member being located rearwardly of said blade with its forward end adjacent to the end of the blade having the opening therein.
- 20 25 3. In a device of the character described, the combination of runners having lower
- edges to engage the surface of a road, and forming side walls to prevent the lateral escape of dirt from between said runners, braces for spacing the runners apart, guides on the inner sides of said runners, a blade 30 engaging said guides at its ends and extending diagonally across between the runners, said blade being cut away at its rearmost end adjacent to one runner to form an opening to permit dirt to pass the blade, means 35 for raising and lowering said blade in its guides, and a leveling member extending between said runners in a diagonal direction opposite to that of the blade rearwardly of said blade with its lower edge in the plane 40 of the lower edges of the runners and its foremost end adjacent to the rearmost end of the blade.

In testimony whereof I affix my signature in presence of two witnesses.

J. F. THEODORE BERGER.
